UNITED STATES PATENT OFFICE.

JAMES MURPHY, OF CHICAGO, ILLINOIS.

FURNACE.

SPECIFICATION forming part of Letters Patent No. 660,274, dated October 23, 1900.

Application filed March 13, 1900. Serial No. 8,448. (No model.)

To all whom it may concern:

Be it known that I, JAMES MURPHY, a citizen of the United States, residing at Chicago, in the county of Cook and State of Illinois, 5 have invented a new and useful Improvement in Furnaces, of which the following is a specification.

My invention relates particularly to boiler-furnaces; and my object is to provide an improved fireproof construction, applicable to either new or old furnaces, whereby a more perfect distribution of air is secured and conditions for more perfect combustion attained.

In the preferred construction the furnace-walls are provided with channels which lead from the ash-pit around the edges of the grate to the combustion-chamber and are in communication with each other near their discharge-orifices.

20 In the drawings, Figure 1 represents a broken vertical longitudinal section of my improved furnace, the section being taken at line 1 of Fig. 2; Fig. 2, a transverse section at line 2 of Fig. 1; Fig. 3, a horizontal section at line 3 of Fig. 1; Fig. 4, an upper perspective view of a fragment of a lower tile-section employed, and Fig. 5 a similar view of an upper tile-section.

25 A, A', and A² represent, respectively, the front wall, side walls, and bridge-wall; B, the grate; B', the combustion-chamber; B², the ash-pit, and B³ the combustion-chamber-door openings. The ash-pit doors are directly beneath the combustion-chamber doors.

30 C C', Figs. 4 and 5, represent a two-section tile, the top section of which is formed with a horizontal half-circular groove or passage a and the lower section of which is formed with a corresponding horizontal half-circular groove a', an intersecting vertical passage a², and a discharge-orifice a³. When the top section is placed on the lower section, a tile is formed having a vertical passage open at the lower end and crossed by the passage a a' 35 and provided with a discharge-orifice at the face adjacent to the combustion-chamber. Preferably the passages a, a', and a² are nearer the outer face of the tile than the inner face, so that the thicker walls are presented toward 40 the fire.

The preferred manner of providing the furnace-walls with the desired channels is to have

or provide a space or channel c c' c² c³ at the inner portion of each wall, said channel running the full length of the wall where the latter is uninterrupted, and to provide short intake-channels d therefor, separated by refractory partitions d' and in communication with the ash-pit, and then to fill the space c c' c² c³ 55 with the tiles C C', so placed that the horizontal channels a a' shall register to form one continuous passage within the wall and extending longitudinally thereof. When so placed, the tiles are supported by the partitions d' and their interiors are in communication with the 60 ash-pit through the intakes d, while their discharge-orifices are in position to distribute air over the entire fire.

65 The side walls and bridge-wall may be provided throughout their length with the improved tiles. Where more than one door is provided for each the combustion-chamber and ash-pit, it is common to leave a portion of the front wall intact between the two sets of doors. This space is utilized in the present construction for placing one or more of the tiles C C', and it may here be observed 70 that said tiles may be placed wherever there is sufficient wall to be recessed to receive them and permit them to extend above and 75 below the grate. The grate may be supported from the tiles in the ordinary manner.

70 It may be stated that the furnace-walls are commonly built of brick, and where an old furnace is to be equipped with my improvements a given number of layers of bricks may be removed from the inner surfaces of the walls to receive the tiles, and then in a lower plane the bricks may be removed at short intervals to form the channels d and tile-supporting columns d'. The tiles afford air-conduits for taking air from the ash-pit and discharging it above the grate.

85 What I claim as new, and desire to secure by Letters Patent, is—

90 1. In a furnace, the combination with a combustion-chamber, ash-pit and grate, of tiles set into the walls at the grate edges and provided with vertical passages and horizontal discharge-orifices, and columns beneath 95 said grate supporting said tiles and affording air-intakes between them, substantially as and for the purpose set forth.

100 2. In a furnace, the combination with a

combustion-chamber, ash-pit and grate, of tiles set into the walls at the grate edges, each comprising a top section provided on its lower surface with a channel, a lower section having a vertical channel and at its top a channel registering with the channel of said top section and crossing said vertical channel,

one of said tile-sections being provided with a discharge-orifice, substantially as and for the purpose set forth.

JAMES MURPHY:

In presence of—

D. W. LEE,

A. D. BACCI.
